UNITED STATES PATENT OFFICE.

NELSON WOODHULL DAVIS, OF PORT JEFFERSON, NEW YORK.

BOTTLE.

SPECIFICATION forming part of Letters Patent No. 664,350, dated December 18, 1900.

Application filed March 14, 1900. Serial No. 8,619. (No model.)

To all whom it may concern:

Be it known that I, NELSON WOODHULL DAVIS, a citizen of the United States, and a resident of Port Jefferson, in the county of Suffolk and State of New York, have invented a new and Improved Bottle, of which the following is a full, clear, and exact description.

This invention relates to improvements in bottles of the class designed to prevent fraudulent reusage; and the object is to provide a simple device in connection with a bottle that when the bottle is emptied of its original contents will clearly indicate that any refilling or partial refilling is fraudulent, thus affording a safeguard and protection to purchasers; and a further object is to utilize the device as a label or advertising medium within the bottle, making it unnecessary to use labels on the exterior of the bottle.

I will describe a bottle embodying my invention and then point out the novel features in the appended claims.

Reference is to be had to the accompanying drawings, forming a part of this specification, in which similar characters of reference indicate corresponding parts in all the figures.

Figure 1 is a sectional elevation of a bottle containing a device embodying my invention. Fig. 2 is a section thereof at right angles to Fig. 1, and Fig. 3 is a perspective view of the combination-level and telltale or safety device employed.

Referring to the drawings, 1 designates the body portion of the bottle, and 2 the neck thereof, the said neck and body portion being substantially of the same length. Extended through the neck and nearly to the bottom of the body portion of the bottle is a tube 3, the upper portion of which—that is, the portion within the neck—is provided with annular corrugations 4, which are shown as ratchet-shaped, with the horizontal shoulder at the lower side. The portion of the tube 3 within the body of the bottle may be provided with the name of the bottler, a trade-mark, or any other advertising matter. I have here shown it as provided with the name of the bottler, and the letters forming the same are cut through the wall of the tube, thus not only serving as an advertising medium, but providing ports for the passage of liquid into the tube.

The upper end of the tube 3 has a flange 5, adapted to engage upon the upper end of the bottle-neck, and to prevent the removal of said tube after once inserting it I employ plates 6, which engage with one of the corrugations of the tube and are inclined upward, their upper ends engaging in notches 7, formed in the interior of the bottle-neck.

Movable on the tube 3 is a safety device 8, consisting of a tube formed in sections, so as to be easily separated one from the other, as will hereinafter appear. When the bottle is filled, this safety device 8 is wholly within the neck portion of the bottle, and at its upper end it has spring-fingers 9, which are curved outward to engage with the smooth inner surface of the bottle-neck and then turned inward, so their ends may engage with the under sides of the corrugations 4. This tube or safety device 8 will also be provided with any suitable advertising matter, the letters of which are cut through the material and preferably are arranged with a portion of each letter on one section and a portion on the other section, so that when the parts are separated the label will be practically destroyed.

Surrounding the tube 3 is a ring-shaped float 10, consisting of cork or other light material, and on the upper side of this float the lower end of the tube or safety device 8 rests. I may temporarily secure the lower ends of the sections forming the part 8 together by means of a light wire ring 11. The tube or safety device 8 is provided with opposite notches 12, in which the plates 6 may engage while the said tube 8 is in its uppermost position, and of course these plates 6 will prevent the removal of said tube 8.

In operation after filling the bottle the tubes 3 and 8 and the float 10 are to be placed in position, as indicated in the drawings, and locked by the plates 6. As the liquid is poured out the float 10 will move downward with the level thereof, permitting the tube or safety device 8 to move downward, so that the spring-fingers 9 will engage with one of the lower corrugations 4, and this will continue until the bottle is wholly empty, and when so wholly empty the tube or safety device 8 will move into the body portion of the bottle and the sections will fall apart, as in-

dicated by dotted lines in Fig. 1, destroying the label and the identity of the bottle as an original package.

Should liquid be poured into the bottle 5 while the tube 8 is partially within the neck 2, the fact will be evident, because the liquid so poured in will rise above the bottom of said tube 8, as the tube will be prevented from moving up by its spring-fingers engaging 10 with the corrugations 4. As the spring-fingers practically fill the space between the outer surface of the tube 3 and the interior of the bottle, it is obvious that the part 8 after once passing into the body of the bottle 15 cannot be returned to the neck. Ports 13 are provided through the upper end of the tube 3 to permit the passage of any liquid that might be contained within the space between said tube and the bottle-neck.

Having thus described my invention, I 20 claim as new and desire to secure by Letters Patent--

1. In a bottle, a safety device adapted to move by gravity in the neck and to the body 25 of the bottle and to fall apart in the body of the bottle, substantially as specified.

2. In a bottle, a tube extended through the neck portion thereof and having exterior corrugations on its portion within the neck, a 30 safety device movable on the tube, the said safety device consisting of a sectional tube adapted to move downward with the lowering of the liquid in the bottle, and spring-fingers on said safety device for engaging with the 35 corrugations.

3. In a bottle, a tube extended through the neck portion thereof and nearly to the bottom of the body portion of the bottle, the part 40 of this tube within the neck having annular corrugations, a safety device movable on the tube and consisting of a sectional tube, spring-fingers on the upper end of said safety device for engaging with the corrugations, and a float surrounding the first-named tube 45 and adapted to support the safety device, substantially as specified.

4. In a bottle, a tube extended through the neck portion thereof and nearly to the bottom of the body portion, the part of said tube 50 within the neck being provided with annular corrugations of ratchet shape, a sectional tube

movable on the first-named tube, spring-fingers on said sectional tube adapted to engage with the corrugations, and also to engage with the interior of the bottle-neck, and a 55 float for supporting the sectional tube, substantially as specified.

5. In a bottle, a tube extended through the neck portion thereof and nearly to the bottom of the body portion, the said tube having 60 advertising devices at its lower portion, a sectional tube movable on the first-named tube, means for preventing the upward movement of the sectional tube relatively to the other tube while any part of the said sectional tube 65 is within the neck of the bottle, and a float movable on the first-named tube and supporting the sectional tube, substantially as specified.

6. In a bottle, a tube extended through the 70 neck portion of the bottle and into the body portion thereof, means for locking said tube in the bottle, a sectional tube movable on the first-named tube, the said sectional tube having advertising matter, the letters of which 75 provide openings through the wall of the tube, portions of the letters being on one section while the other portions are on the other section, and means for preventing an upward movement of the sectional tube relatively to 80 the first-named tube, substantially as specified.

7. In a bottle, a tube extended through the neck portion and into the body thereof, the part of said tube within the body having ad- 85 vertising matter, the letters of which form ports, a sectional tube movable on the first-named tube, means for preventing an upward movement of the sectional tube relatively to the first-named tube when any portion of said 90 sectional tube is within the neck of the bottle, and means for preventing the withdrawal of either of said tubes from the neck of the bottle, substantially as specified.

In testimony whereof I have signed my 95 name to this specification in the presence of two subscribing witnesses.

NELSON WOODHULL DAVIS.
